UNITED STATES PATENT OFFICE

111,625

DESIGN FOR A TEXTILE FABRIC OR SIMILAR ARTICLE

Bruno H. Barth, West Englewood, N. J., assignor to William Kerbs Kalman, doing business as Blanck & Co., New York, N. Y.

Application August 30, 1938, Serial No. 79,628

Term of patent 3½ years

To all whom it may concern:

Be it known that I, Bruno H. Barth, a citizen of the United States, residing at West Englewood, New Jersey, have invented a new, original, and ornamental Design for a Textile Fabric or Similar Article, of which the following is a specification, reference being had to the accompanying drawing, forming a part thereof.

The figure is a plan view of a textile fabric showing my new design. The dot and dash lines on the drawing outline substantially a design unit, which unit is repeated in regular succession as indicated by the extensions beyond the unit boundaries.

I claim:

The ornamental design for a textile fabric or similar article, as shown and described.

BRUNO H. BARTH.
